CASPER BLOOMBERG, OF NEW YORK, N. Y., ASSIGNOR TO PIONEER SUSPENDER COMPANY, A CORPORATION OF PENNSYLVANIA.

GARTER.

Application filed July 20, 1926. Serial No. 123,666.

- My invention relates to improvement in garters made of leather, textile fabric elastic webbing and metal trimmings and it is my object to produce an improved garter in which the leather face portions of the pad will be protected from perspiration from the body of the wearer, thereby preventing soiling and discoloration and hardening and disintegration of said leather face portion.
- 5 In the drawing Fig. 1 is a plan view of my improved garter; Fig. 2 a back view of the pad; and Fig. 3 a sectional view, on an enlarged scale of the structure of Fig. 2 on the line 3—3 thereof.
- 10 The garter comprises the pad 1, the leg encircling band 2 and the tab 3. A slide 4 on the band 2 enables the wearer to adjust the length of the garter, while a loop 5 on the free end is adapted to engage a button 6 on the pad to secure the garter on the leg. A loop 7 and button 8 on the tab 3 serve to secure the garter to the sock.
- 15 As is best shown in Fig. 3 the pad 1 consists of a piece of leather 9, forming the face, a piece of fabric 10 forming the back, and moisture-proof material 11, interposed between and entirely separating the leather face from the fabric back. The end of the band 2 and the end of the tab 3 are secured between the leather and fabric as shown, so that the fabric 10 will come next to the skin of the wearer. By means of this construction the leather face 9 is protected from discoloration, hardening and disintegration from body moisture, and the back is a textile fabric which does not cause discomfort to the wearer.
- 20 Lines of stitching 12 serve to secure the leather face, the fabric backing, the band and the tab together.
- 25 I claim:—
- In a garter, the combination with a leg band and a stocking supporting clasp, of a pad comprising a leather face and a textile fabric back with moisture-proof material 30 interposed between and entirely separating the material of the face from the material of the back.
- 35 In testimony whereof I have affixed my signature.
